UNITED STATES PATENT OFFICE

VIRGINIA A. WHITE, OF DALLAS, TEXAS

ABDOMINAL SUPPORT OR CORSET

Application filed May 23, 1929. Serial No. 365,262.

This invention relates to improvements in corsets and one of the objects thereof is to provide a corset of light weight, strongly made and particularly adapted to use during 5 maternity and after surgical operations.

A further object of the invention is to provide an improved corset having an abdominal supporting feature.

Another object is to provide a garment of 10 this character which may be readily put on or taken off.

A still further object of the invention is to provide a corset possessing extreme flexibility and adaptability to adjustments for 15 reducing the figure.

Another object of the invention is to provide a corset having means for retaining the hips in graceful lines and for reducing abnormal conditions or growths on the hips.

20 Other objects will be apparent from the following detailed description.

With the above objects in view, the invention will be clearly understood from a perusal of the following detailed description, 25 taken in connection with the accompanying drawings, forming part of this specification, and wherein:

Figure 1 is a view of the corset in position upon the wearer, and

30 Figure 2 is a general view of the corset, partly in perspective and partly in elevational view to show its construction.

Proceeding in accordance with the drawings, the garment consists of a strong, soft 35 fabric rear body portion 1 with spaced longitudinally arranged pockets 2 wherein are disposed the usual staves 3. The garment includes a waist line 4, and 5 indicates the lower edge of the corset, the garment 40 being as narrow as possible, consistent with ample abdominal supporting and form reducing proportions as will become apparent as the description proceeds.

Attached to the body portion 1 by means 45 of the pliable connection 6 is the abdominal supporter 7, suitably reinforced by the tapes 8. The abdominal supporter includes a waist line 4, and the lower edge 9 of the supporter is curved to follow the contour of 50 the lower portion of the abdomen. A flap

10, provided with eyelets 11, is provided for convenient and quick connection or disconnection of the abdominal support from the body portion of the garment, in conjunction with the hooks 12. There are also included in the construction of the garment, straps and buckles 13 and 14. The strap and buckle arrangement is for the use of physicians or surgeons, who adjust these fastenings for permanent position until such 55 time as the patient has recovered.

It will be readily understood that by the use of the hook and eyelet arrangement, the garment can be put on or taken off without the necessity of slipping the garment over 60 the head.

The abdominal support can be readily adjusted to reduce the abdomen by means of the lacings 15 in the splits 16 on each side of the supporter. Likewise these lacings 70 provide convenient means for adjusting the garment in reducing or in fitting the corset upon the figure.

One of the particular features of the corset is the hip reducing means, provided by 75 the portions 17 connected to the body of the garment by means of the lacings 18. In this arrangement, the portions or wings 17 are provided on their inner connecting ends with rubber webbing 19 and have the usual 80 hook and eyelets 20 and 21.

The portions 17 when adjusted by the lacings to the proper tightening effect, aid in reducing the hips and in keeping the hips in graceful lines. The hip control arrangement also aids in the removal of fatty tumors by proper adjustment of the lacings 18.

There is also included in the construction of the garment sufficient rubber webbing 23 as will obviate any splitting or undue strain 85 on the garment in sitting or other postures where a strain would come.

From the foregoing it will be apparent that the corset includes features whereby any adjustment may be made to properly fit the garment to the body. The garment is light in weight and can be put on and removed quickly and easily. There are no unnecessary or cumbersome parts and the corset is also economical of manufacture. 90

The garment is susceptible of some variations in structure, such as will be within the scope and intent of the appended claim.

What is claimed as new is:

- 5 A corset having a suitably braced body portion encircling the back of the figure and overlapping the hips, the upper edge of the corset being on the waistline of the figure and the lower edge of the corset extending 10 to a point below the hips, pliable connecting strips at each side of the body portion, an abdominal supporter connecting said pliable side strips, said abdominal support having an unbroken front and a lower edge curved to 15 follow the contour of the lower part of the abdomen, a quick detachable means at one side only of said abdominal support, comprising hook and eye members, buckle and strap means for relatively permanently adjusting said pliable connecting strips, means for adjusting the lower part only of 20 said abdominal support, comprising a pair of laced slits, one adjacent each side thereof, and extending partway from the lower 25 edge of the abdomen support upwardly, but terminating short of the waistline, and wing portions connected to the body portion of the corset located below and separate from the abdominal support, said wing portions 30 having adjusting means for the control of the hips, the adjusting means comprising a pair of laced slits located immediately below said pliable connecting side strips.

In testimony whereof I affix my signature.
